UNITED STATES PATENT OFFICE.

SARAH J. SCHACK, OF CHICAGO, ILLINOIS.

DESIGN FOR A CHILD'S WAIST.

SPECIFICATION forming part of Design No. 23,132, dated March 20, 1894.

Application filed October 14, 1893. Serial No. 488,188. Term of patent 14 years.

To all whom it may concern:

Be it known that I, SARAH J. SCHACK, a citizen of the United States, residing at Chicago, in the county of Cook and State of Illinois, 5 have invented or produced a new and original Design for a Child's Waist, of which the following is a specification.

This design has for its object to provide a child's waist possessing a peculiar shape or 10 form which is novel and ornamental.

The leading feature of the design resides in a child's waist composed of a flat central portion having widening end portions, the lower and upper edges of which extend upward, so 15 that all of said edges are at obtuse angles to the parallel lower and upper edges of the flat central portion, thus giving the end portions of the band the appearance of bodily extending obliquely to the flat central portion.

20 The design is illustrated by the accompanying drawing, in which the figure is a plan view of the child's waist.

In the drawing the letter *a* indicates the central flat body portion, and *b* and *c* the widening end portions, the lower edges *e*, and 25 the upper edges *d* of which all extend upward and are at obtuse angles to the parallel lower and upper edges of the flat central portion *a*, whereby the end portions are given the appearance of bodily extending obliquely to the 30 flat central portion.

The design provides a novel and ornamental child's waist which presents a peculiar and distinguishing appearance.

What I claim is—

35 The design for a child's waist, substantially as shown and described.

SARAH J. SCHACK.
